UNITED STATES PATENT OFFICE.

CHARLES T. BRADSHAW, OF PHILADELPHIA, PENNSYLVANIA, ASSIGNOR TO
THE AUTOMATON ADVERTISING COMPANY, OF CAMDEN, NEW JERSEY.

DESIGN FOR A DISPLAY-FIGURE.

SPECIFICATION forming part of Design No. 32,674, dated May 15, 1900.

Application filed July 27, 1899. Serial No. 725,327. Term of patent 3½ years.

To all whom it may concern:

Be it known that I, CHARLES T. BRADSHAW, a citizen of the United States, residing at Philadelphia, in the county of Philadelphia, State of Pennsylvania, have invented and produced a new and original Design for a Display-Figure, of which the following is a specification, reference being had to the accompanying drawing, forming part thereof.

10 The figure of the drawing is a perspective view of a display-figure, showing my new design.

As shown in the drawing, the leading or material feature of my design consists of the representation of a child A, holding a pipe B in one hand, in the act of blowing a soap-bubble C, and holding a fan D in the other

hand. The pipe B is inverted and the bubble C is suspended from the bowl thereof. The fan D is in position to blow the bubble away 20 if operated. In front of the child is placed a table E, supporting bowls II. The child and table are supported on a base or pedestal I.

Having described my invention, what I 25 claim as new, and desire to secure by Letters Patent, is—

The design for a display-figure, substantially as herein shown and described.

CHARLES T. BRADSHAW.
